UNITED STATES PATENT OFFICE.

THADDEUS B. KEELER, OF RAHWAY, NEW JERSEY, ASSIGNOR TO THE STANDARD RAILROAD SIGNAL COMPANY, OF TROY, NEW YORK.

MOTOR-ACTUATED SIGNAL.

SPECIFICATION forming part of Letters Patent No. 643,824, dated February 20, 1900.

Application filed May 10, 1899. Serial No. 716,214. (No model.)

To all whom it may concern:

Be it known that I, THADDEUS B. KEELER, a citizen of the United States, and a resident of Rahway, in the county of Union and State 5 of New Jersey, have invented a new and useful Improvement in Motor-Actuated Signals, of which the following is a specification.

My invention relates to a motor-actuated signal and includes the subject-matter of my 10 pending application, Serial No. 708,503, but goes further and provides for the automatic movement of the actuating-wheel to complete its revolution ready for prompt action when the signal is to be set to "safety." It also 15 provides for locking the blade against unintentional dropping under the weight of snow and ice or other foreign substance and for positively returning the blade to its normal or danger position in the event of the blade 20 failing to return when released under the influence of gravity. I do not, however, wish to be understood as limiting the subject-matter of my present application to the particular form of motor-signal which I have 25 chosen to illustrate its practical application, as some or all of the features may be applied either directly or with obvious modifications to other forms.

The accompanying drawing represents in 30 side elevation the arrangement of parts which I find eminently practicable, the cover of the casing being removed to show the operating mechanism and the electric circuits being diagrammatically represented in connection with 35 the parts within the casing.

The parts are represented in the drawing in their normal positions, with signal at "danger."

The supporting-post is denoted by A, the 40 signal-blade by B, its counterbalance by B', and the point where the blade is pivotally attached to the post is denoted by b.

A supporting-piece C is secured to rock 45 with the blade and has attached thereto the rocking latch c, the rocking detent c', and the electromagnet c², which latter, through its armature c³, operates upon one arm of the detent c' to lock and release the latch c as the electromagnet c² is energized or deenergized.

50 The nose of the latch c engages a recess d in

the curved rim d' of a rocking segment D, mounted on the shaft b of the signal-blade to move independently of the signal-blade whenever released therefrom by the latch.

The segment D is positively operated by 55 means of a pitman d², which connects it with a crank-arm e on a worm-wheel E, mounted on a suitable axle within the casing F. The worm-wheel E is actuated by a worm g on the shaft of a motor, in the present instance an 60 electric motor G, also suitably supported within the casing F.

A bar-spring H is fixed within the casing F with its free curved end in position to press 65 against the end of the pitman d² on the crank e with just sufficient force to arrest the motion of the worm-wheel when the power has been cut off from the motor to prevent the worm-wheel from moving too far under its momentum.

The main controlling electric circuit, which 70 may be assumed to come from a signal-tower, (not shown,) is represented by the wires K K', the latter leading directly to one pole of the electromagnet I, and the former, by means of 75 wires k k', leading to and through the electromagnet c² and thence to the opposite pole of the electromagnet I. This arrangement places the electromagnet c², which controls the de- 80 tent c' for locking and releasing the latch c, in the main controlling-circuit, so that the electromagnets I and c² are simultaneously energized or deenergized by the closing or opening of the main controlling-circuit K K'.

The armature I' of the magnet I normally 85 engages a contact-point l and closes circuit through a battery M and an electric circuit including said battery, the electric motor G, and a pair of contact-arms N N'. This circuit may be traced as follows: from one pole 90 of the battery M, along to one pole of the electric motor G, thence from opposite pole of motor G, along wire L' to contact-arm N', thence from contact-arm N, along wire L² to contact-point l, and thence through armature 95 I' and wire L³ to opposite pole of battery M. The contact-arms N N' are one or both of them preferably made of resilient material—brass, for example—and the arm N' is held normally 100 out of contact with the arm N, thus forming

a break in the back contact-circuit hereinabove last described.

Where the electromagnet I is energized, its armature I' closes contact between two contact-pieces $o\ o'$ in circuit with battery M, motor G, and a pair of contact-pieces $p\ p'$ in the switch-bar P. This circuit may be traced as follows: from contact o , through wires O and L^3 , to battery M, thence along wire L to motor G, thence along wires L' and O' to contact p , thence to contact p' and along wire O^2 to contact o' .

When the signal is at danger position, the contact-pieces $p\ p'$ are held closed by suitable mechanical mechanism under the control of the signal-blade, in the present instance by a cam q , arranged to be rocked by any well-known means connecting it with the blade, and when the blade is dropped into safety position the cam q will permit the contact-piece p' to spring away from the piece p and break circuit.

The operation is as follows: Suppose the parts to be in the normal position represented 25 in the drawings, with the signal-blade at "danger" and the main controlling-circuit open. The operator wishing to set the signal at "safety," for example, to permit a train to pass closes the circuit K K', thereby simultaneously energizing the electromagnets I and c^2 . The latter locks the latch c by means of the detent c' and the former draws the armature I' away from the contact-point l and closes circuit between the contact-pieces $o\ o'$. 30 This completes circuit through battery M, motor G, and contact-pieces $p\ p'$, thereby setting the motor in operation, rotating the worm-wheel E, and by means of the pitman d^2 rocking the segment D and the signal-blade, locked thereto, down into the safety position. As the blade B approaches the safety position the cam q , rocked by the movement of the blade, breaks contact between the pieces p and p' , and thereby breaks the circuit which is for the moment actuating the motor G, and the signal remains at "safety." 35 When the operator, for example, after the train has passed, wishes to return the signal to "danger," he opens the main circuit K K', thereby deenergizing the magnets I c^2 . The latter releases the detent c' , which in turn releases the latch c and permits the blade B to return to danger position under the weight of its counterbalance B'. The former, I, permits the armature I' to drop into engagement with the contact-point l , and thereby closes circuit through the battery M, motor G, and contact-arms $N\ N'$, which latter have been permitted to come into engagement by the 40 lifting of the pitman d^2 and the arm of the segment D, to which it is attached. This will again start the motor and continue the rotation of the worm-wheel and positively rocking the segment D back into its normal position, ready for prompt action when it is again to be moved to "safety." As the segment D 45 nears the completion of its return movement

it draws the contact-arm N' away from the arm N , thereby breaking circuit through the motor, the momentum of which is overcome by the pressure of the spring H on the end of the pitman d^2 . The return of the segment D to its normal position immediately upon the opening of the main controlling-circuit K K' serves to bring the latch c into engagement with the recess d in the segment, and thereby prevents the blade from dropping under weight of snow and ice or other foreign matter, since the engagement of the latch with the segment is such that while it permits the blade to rise independently of the segment when the detent c' is released it will not permit the blade to drop independently of the segment when the nose of the latch is in the recess d . Furthermore, the continued movement of the worm-wheel and consequent return movement of the segment will positively return the blade B from its safety to its danger position whenever from any cause it may have failed to release itself from the segment and return under gravity.

In speaking of the operation of the signal I have assumed an operator at a tower or signal-station. In using the signal in connection with an automatic system where a track-circuit under the control of a train is utilized a suitable track instrument would take the place of the operator in closing and opening the main controlling-circuit.

What I claim is—

1. A motor-signal comprising a signal-blade mounted to tilt, a motor for actuating the signal, a main signal-controlling circuit, a primary circuit through the motor and a second circuit through the motor under the control of the main signal-controlling circuit for automatically operating the motor for a predetermined period after the main controlling-circuit is broken, substantially as set forth.

2. A motor-signal comprising a signal-blade mounted to tilt, a motor, a rocking segment under the control of the motor, means for locking the rocking segment to and releasing it from the signal-blade, a main signal-controlling circuit, a primary circuit through the motor and a second circuit through the motor for automatically returning the rocking segment to its normal position when the main circuit is broken, substantially as set forth.

3. A motor-signal comprising a signal-blade mounted to tilt, a motor-signal-actuating mechanism under the control of the motor, a main signal-controlling circuit, a primary circuit through the motor, a second circuit through the motor and circuit-closing mechanism under the control of the said signal-actuating mechanism to close the second circuit through the motor when the main controlling-circuit is broken, substantially as set forth.

4. A motor-signal comprising a blade mounted to tilt, a motor, signal-actuating mechanism under the control of the motor to tilt the blade, a main signal-controlling circuit, an

electromagnet included in said circuit, a primary circuit through the motor and a second circuit through the motor and including the armature of the said magnet as a part of the 5 circuit, said second circuit being completed on the opening of the main circuit through a back contact of said armature, substantially as set forth.

5. A motor-signal comprising a signal-blade, 10 a motor, signal-actuating mechanism under the control of the motor, means for connecting said signal-actuated mechanism to and releasing it from the blade, a main signal-controlling circuit for locking the signal-actuating mechanism to and releasing it from 15 the blade, an electromagnet included in said circuit, a primary circuit through the motor, a second electromagnet in the main signal-controlling circuit for completing the circuit 20 through the motor, and a second circuit through the motor under the control of said second electromagnet to be closed when the

main circuit is opened, substantially as set forth.

6. The combination with the signal-operating mechanism, the motor engaged therewith, the primary circuit through the motor, the main controlling-circuit for energizing the motor-circuit and an electromagnet included in said main controlling-circuit, of a second 25 electric circuit through the motor, including the armature of said electromagnet, and contact-pieces included in said second electric circuit under the control of the signal-operating mechanism to be closed and opened, substantially as set forth.

In testimony that I claim the foregoing as my invention I have signed my name, in presence of two witnesses, this 5th day of May, 1899.

THADDEUS B. KEELER.
